United States Patent Office

CHARLES T. SMITH, OF UTICA, NEW YORK.

Letters Patent No. 64,158, dated April 23, 1867.

IMPROVEMENT IN METALLIC BOBBINS.

The Schedule referred to in these Letters Patent and making part of the same.

TO ALL WHOM IT MAY CONCERN:

Be it known that I, CHARLES T. SMITH, of Utica, Oneida county, New York, have invented a new and useful Improvement in Metallic Bobbins; and I do hereby declare that the following is a full, clear, and exact description thereof, which will enable others skilled in the art to make and use the same, reference being had to the accompanying drawings, forming part of this specification.

This invention relates to a new and useful improvement in the construction of metallic bobbins, patented by me October 16, 1866. The present invention consists in the means employed for securing the wooden heads or flanges on the metallic tubes, as hereinafter fully shown and described. In the accompanying sheet of drawings—

Figure 1 is a longitudinal central section of a metallic warp bobbin, having the head or flange secured upon its tube according to my invention.

Figure 2, an external view of a metallic twist bobbin, having the head or flange secured upon its tube in the same way.

Figure 3, an external view of a shuttle bobbin, having the head or flange secured upon its tube in the same way.

Similar letters of reference indicate corresponding parts.

The tubes *a* are, as hitherto, constructed of zinc or other non-corrosive metal. Zinc would probably be the cheapest and preferable material, although brass would answer a good purpose. The tubes are drawn down to the proper dimensions, and the interior of the upper ends of the tubes *a* are filled with solder, *e*, or other suitable material, (see fig. 1,) so that the interior of the orifices of the tubes may be contracted to suit the upper part of the spindle on which the bobbin is fitted while being filled. In lieu of this, however, the tubes may be drawn with solid heads or tips, and the latter drilled out to suit the diameter of the ends of the spindle. These features, however, are shown and described in the Letters Patent previously granted to me, and therefore do not require a more minute description.

The wooden heads or flanges *b* are fitted on the tubes *a*, and firmly secured thereon by having the tubes *a* drawn so as to form a shoulder, *c*, the metal being compressed or forced down so as to form a short concave in the exterior of the metal, the metal displaced forming the shoulder. The upper surfaces of the heads or flanges *b* abut against the shoulders *c*, and the lower ends of the tubes *a* project a trifle below the under surfaces of the heads or flanges, and are turned over within a concave, *d*, in the under surfaces of the heads or flanges, as shown clearly in fig. 1. If necessary or desired the ends of the tubes *a* may be slotted longitudinally a short distance, and the portions formed by the slots turned over within the concave. By this simple means the heads or flanges will be firmly secured on the tubes.

I claim as new, and desire to secure by Letters Patent—

The securing of the wooden heads or flanges *b* on the non-corrosive metal tubes *a*, of bobbins, by drawing up a shoulder, *c*, on the tubes, for the upper surfaces of the heads or flanges *b* to abut against, and turning up the ends of the tubes *a*, within a concave, *d*, substantially as shown and described.

The above specification of my invention signed by me this 2d day of February, 1867.

CHARLES T. SMITH.
